UNITED STATES PATENT OFFICE.

FRANK J. CALLAN, OF BOSTON, MASSACHUSETTS.

QUICK-ACTING PIPE-VISE.

1,112,192.

Specification of Letters Patent.

Patented Sept. 29, 1914.

Application filed May 18, 1914. Serial No. 839,345.

To all whom it may concern:

Be it known that I, FRANK J. CALLAN, a citizen of the United States, residing at Boston, in the county of Suffolk and State of Massachusetts, have invented a new and useful Improvement in Quick-Acting Pipe-Vises, of which the following is a specification, reference being had to the accompanying drawings.

10 This invention has for its object to provide a vise the jaws of which may be quickly closed and opened and are automatically locked when closed, the jaws being preferably adapted to hold cylindrical bodies, and 15 the vise being especially adapted for the use of plumbers.

The invention consists in the improvements which I will now proceed to describe and claim.

20 Of the accompanying drawings forming a part of this specification: Figure 1 represents a side view of a vise embodying my invention, the jaws being closed upon a length of pipe; Fig. 2 represents a similar 25 view, showing the jaws opened; Fig. 3 represents a top plan view; Fig. 4 represents a section on line 4—4 of Fig. 2, looking toward the right; Fig. 5 represents a section on line 5—5 of Fig. 3; Fig. 6 represents a section on line 6—6 of Fig. 2, looking toward the right; Fig. 7 represents a perspective 30 view of one of the jaw facings herein-after referred to; Fig. 8 represents a plan view of the adjustable toggle link shown by 35 Figs. 1, 2 and 3, the nut portion thereof being in section; Fig. 9 represents a side elevation of a modified form of operating lever.

The same reference characters indicate the same or similar parts in all the views.

40 1 represents a flat base adapted to be attached to a bench or other support and provided at one end portion with a fixed jaw 2, and at the opposite end portion with a fixed standard spaced at a considerable distance 45 from the fixed jaw, and preferably composed of two spaced-apart side members 3 connected by a transverse web 3^a. The base 1 is provided, between the fixed jaw and the standard, with longitudinal guides 4, with 50 which are slidingly engaged grooved ears or runners 14 formed on or attached to a movable jaw 13, opposed to the fixed jaw 2. The opposed sides of the jaws 2 and 13 may be provided with coinciding recesses 6 and 7, 55 adapted to receive lengths of pipe of different diameters, said recesses being preferably formed in Babbitt metal face plates 5 having flanges 9 which are screwed to the ends of the jaws. Said cavities may have grooves 8, as shown by Figs. 5 and 7, to hold resin or 60 other frictional material.

The movable jaw 13 is connected with the fixed standard 3 by a toggle, one of the links of which is preferably adjustable in length, and is formed as a turnbuckle composed of oppositely screw-threaded sections 19 and 20, and a nut 21 threaded to engage said sections. The section 20 is connected by a pivot or knuckle pin 26 with the other link of the toggle, said link being preferably 70 composed of two members 30 connected by a hub 30^a (Fig. 4). One end of the toggle is connected by an outer pivot 17 with an ear 16 on the movable jaw 13, and the opposite end of the toggle is connected by an inner pivot 28 with the standard 3. The pivots 17 and 28 are in a plane substantially parallel with the base 1, so that the toggle, when in its active position with its links in or approximately in alinement with each other, 75 stands substantially parallel with the base.

31 represents a manually operated operating lever connected by a fulcrum pin 29 with the standard 3. Said lever is connected with the toggle by a link 34 engaged at one 85 end with the knuckle pin or pivot 26 of the toggle, and at the other end with a pivot 35 carried by the lever 31, and preferably by ears 32 projecting from the lever so that the pivot 35 is offset as shown by Figs. 1 90 and 2.

The inner toggle pivot 28 and the lever fulcrum pin 29 are in a plane at an angle to the base 1, and the arrangement of the described parts is such that a movement of the 95 lever 31 to the position shown by Fig. 2 forces the toggle to a position of rest with its links radically out of alinement with each other, and retracts the movable jaw from the fixed jaw, thus opening the jaws. 100 A movement of the lever to the position shown by Fig. 1 forces the toggle to its active position with its links in or approximately in alinement with each other, and projects the movable jaw toward the fixed 105 jaw, thus closing the jaws.

It will be seen by reference to Figs. 1 and 2 that when the lever 31 is in its jaw-opening position the pivot 35 is at one side of the plane in which the inner pivot 28 and fulcrum 29 are located, and that when the lever is in its jaw-closing position the pivot 35 is

at the opposite side of said plane, as shown by Fig. 1. The lever is held in the last described position by its own weight, which is sufficient to prevent the toggle knuckle from 5 moving toward its position of rest. The lever therefore confines the toggle in its active position and maintains any closing pressure that may have been imparted by the lever through the link and toggle to the movable 10 jaw. The confining action, caused simply by the movement of the lever from one position to the other, is automatic.

The vise may be conveniently adjusted to hold different sizes of pipe by varying the 15 length of the turnbuckle link of the toggle.

The hand lever may be of the bell-crank form shown by Fig. 9, in which 31^a represents the longer arm and 37 the shorter arm, the ears 32^a, which hold the pivot 35, being 20 formed on the shorter arm.

Having described my invention, I claim:

1. A vise comprising a base having a fixed jaw, and a fixed standard spaced from said jaw, a movable jaw slidably engaged with 25 the base between the fixed jaw and the standard, a toggle connected by an outer pivot with the movable jaw and by an inner pivot with the standard, and manually operated means for forcing the toggle to a position of rest with the jaws opened, and to an active position with the jaws closed, said means having provisions for automatically 30 confining the toggle in its active position.

2. A vise comprising a base having at one 35 end portion a fixed jaw and at the opposite end portion a fixed standard, a movable jaw slidably engaged with the base between said fixed jaw and standard, a toggle connected by an outer pivot with the movable 40 jaw and by an inner pivot with the standard, said outer and inner pivots being on a

plane substantially parallel with the base, a hand lever fulcrumed on the standard at a distance from the said inner pivot, the lever fulcrum and inner pivot being on a plane at 45 an angle to the base, and a link pivoted at one end to said lever and at the opposite end to the toggle knuckle and adapted to coöperate with the lever in forcing the toggle to a position of rest with the jaws opened and 50 to an active position with the jaws closed, the arrangement being such that the weight of the lever is adapted to confine the toggle in its active position.

3. A vise comprising a base having a fixed 55 jaw and a fixed standard spaced from the fixed jaw, a movable jaw slidably engaged with the base between the fixed jaw and the standard, a toggle connected by an outer pivot with the movable jaw and by an inner 60 pivot with the standard, and means for forcing the toggle to a position of rest, with the jaws opened, and to an active position with the jaws closed, the toggle being adjustable in length to vary the closing movement of the movable jaw.

4. A vise comprising a base having a fixed jaw and a fixed standard spaced from the fixed jaw, a movable jaw slidably engaged with the base between the fixed jaw and the 70 standard, a toggle connected by an outer pivot with the movable jaw and by an inner pivot with the standard, and means for forcing the toggle to a position of rest, with the jaws opened, and to an active position with 75 the jaws closed, one of the toggle links being a turnbuckle adapted to vary the length of the toggle.

FRANK J. CALLAN.
